UNITED STATES PATENT OFFICE.

F. A. BALCH, OF HINGHAM, WISCONSIN.

STOVE-PIPE DRUM OR HEAT-RADIATOR.

Specification forming part of Letters Patent No. 56,514, dated July 24, 1866.

To all whom it may concern:

Be it known that I, F. A. BALCH, of Hingham, in the county of Sheboygan and State of Wisconsin, have invented a new and useful Improvement in Heat-Radiators for Stoves; and I do hereby declare the following to be a full, clear, and exact description of the same, reference being had to the accompanying drawings, in which—

Figure 1 is an elevation of my radiator, one portion being represented in section, so as to exhibit the construction of the interior. Fig. 2 is a transverse section on line *x x*.

My invention relates to that class of radiators in which the heat is designed to be absorbed by air which is confined within the walls of the structure, and afterward admitted into the room in which the radiator is located or conducted into other apartments; and it consists in conducting the pure-air pipes lengthwise through the midst of the smoke-pipes, so that the said smoke-pipes may radiate heat into the surrounding atmosphere at the same time that pure air is heated within the structure and conducted wheresover it is desired.

It consists, also, in constructing the radiator with a hot-air chamber at its top, from which the air heated by its passage through the pure-air pipes may be conducted into other rooms, admitted directly into the surrounding atmosphere, or allowed to pass into the smoke-pipe, and thus escape when, owing to the temperature of the atmosphere, it is not desired to utilize all of the heat from the fuel.

That others may understand my invention, I will particularly describe it.

My invention consists generally of two drums, A and B, connected by several pipes, C C C. Each of these drums is divided longitudinally by partitions D and E, so as to divide said drums into smoke-chambers F F' and pure-air chambers G G'. The chambers G G' are connected by pipes H H, which are smaller in diameter than and pass lengthwise through the pipes C C, so as to leave a space all around the pipe H between it and the pipe C.

The smoke-funnels I I' enter and leave the radiator, passing through the chambers G and G', as represented, so that, as will be perceived, the products of combustion enter the chamber

F, ascend through the pipes C C, surrounding the pipes H H, into the chamber F', and thence pass off through the funnel I', while pure air may be received from the surrounding atmosphere of the room or through a proper pipe from the atmosphere outside of the building and passed through the pipes H H into the chamber G', whence it may be admitted into the surrounding atmosphere by uncovering the register-holes J J, or it may be conducted through the pipe K to any other part of the building.

It is sometimes desirable that the heat from the stove should pass off freely, as during those seasons when but little fire is needed to maintain a comfortable temperature in the room. I then employ the slide L, which permits the hot air within the chamber G' to flow into the smoke-funnel I', and thus escape; or the central pipe, M, may be introduced, having a valve or valves, so that the products of combustion may be permitted to flow directly through said pipe without heating the drum.

If it be desired to make a closed connection between the pipe M and the pipes I and I', so that none of the heat shall pass through the pipes C C, it may be accomplished by a sliding sleeve on either M or I and I', or by a flap-valve, which may close an orifice in the pipe I opposite the smoke-chamber. In that arrangement the pipe I would be continuous through the drum, and would be provided with a cut-off damper, to prevent any direct passage through it.

The lower chamber, G, may sometimes be dispensed with, and the lower ends of the pipes H H permitted to open directly into the atmosphere surrounding. It is preferred, however, to construct this drum with the chamber G, because then vapors arising from the stove, as in cooking, &c., can be excluded from the drum and pure air introduced from without the building, if necessary.

The induction and eduction pipes N and K are both provided with cut-off valves or dampers.

The orifices O and P, covered by slides, are for the purpose of permitting the soot, &c., to be removed from the smoke-chambers F and F' without trouble.

Having described my invention, what I claim as new, and desire to secure by Letters Patent, is—

1. The pure-air chambers G and G', connected with each other by the pipes H H, which pass through the smoke-pipes C C, substantially as shown.

2. The pure hot-air chamber G', provided with the register-holes J J, the valved flue K, and the valve L, substantially as described.

3. A radiator with the pure-air chambers G and G', the smoke-chambers F and F', the smoke-pipes C C, and the pure-air pipes H H, constructed and arranged substantially as described and shown.

F. A. BALCH.
